LAMP SOCKET

Herman H. Heidkamper, Kalamazoo, Mich.

Application September 5, 1940, Serial No. 355,509

1 Claim. (Cl. 173—328)

This invention relates to an improved construction of lamp socket for high voltage fluorescent interior lighting lamps and aims to provide a form of socket which may be used by the general public for removing, applying or replacing a fluorescent lamp without employing the services of a skilled electrician or service man, as is now generally required.

Still another aim of the invention is to provide a construction of lamp socket by means of which a neat installation may be accomplished with all contacts concealed.

Other objects and advantages of the invention will hereinafter become more fully apparent from the following description of the drawing, which illustrates a preferred embodiment thereof, and wherein:

Figure 1 is a side elevational view partly in section showing a fluorescent lamp mounted between a pair of lamp sockets constructed in accordance with the invention.

Figure 2 is an enlarged fragmentary vertical sectional view, partly in elevation, showing one of the lamp sockets attached to an end of a fluorescent lamp.

Figure 3 is an enlarged fragmentary view partly in section and partly in elevation showing a portion of one of the lamp sockets attached to an end of the lamp, and

Figure 4 is an end view in elevation looking toward the clip of one of the lamp sockets.

Referring more particularly to the drawing, wherein like reference characters designate like or corresponding parts throughout the different views, 10 designates generally a suitable base member on which is mounted a pair of housing or casing members 11 which are disposed in spaced apart relationship relatively to one another and which are provided at their adjacent sides with aligned openings 12 for receiving socket members 13 of non-conducting material such as porcelain. The socket members 13 are each provided with a flanged outer end 14 for engaging the outer side of the wall of the casing or housing 11 in which the opening 12 is formed. The socket members 13 are each externally threaded at 15 to receive a strand of wire 16 which is coiled to form threads for engaging the threads 15 and which is provided withoutwardly projecting U-shaped terminals 17 which engage the inner side of the aforementioned wall of the casing 11 for holding the socket 13 in position in the opening 12. It will thus be seen that the strands of wire 16 are constructed and arranged to form nuts.

The sockets 13 are each provided with a recess 18 which opens outwardly of its flanged end 14 and which, as illustrated, diverges toward its open, outer end. The sockets 13 at their inner ends are provided with wall portions 19, each of which is provided with a contact post 20 formed of a nut and bolt. An expansion coil spring 21 is disposed in each of the recesses 18 and attached at one end to the contact post 20 which is associated with the socket 13 which is provided with said recess.

A metallic spider 22 formed of two pairs of crossed arms has a central opening through which projects a bolt 23 which is provided with a substantially flat head between which and the spider 22 is disposed a washer 24. A disk 25 and nut 26 is carried by the shank end of the bolt 23 and the opposite end of the spring 21 is clamped between the disk 25 and the outer side of the spider 22. The ends of the arms of the spider 22 are bent outwardly and extend in the same direction to form spring fingers 27 which are adapted to yieldably engage the metallic end 28 of a fluorescent high voltage lamp 29. The fluorescent lamp 29 is of conventional construction and contains a filament, not shown, which is electrically connected to the metallic end or cap 28.

From the foregoing it will be obvious that one end of the fluorescent lamp 29 may be inserted into the recess 18 of one of the sockets 13 and the metallic member 28 thereof inserted into and resiliently engaged by the spring fingers 27 of the spider 22 which is disposed within said socket. The fluorescent lamp 29 is then pressed inwardly of said socket 13 to compress the spring 21 thereof sufficiently so that the opposite end of the fluorescent lamp may be inserted into the recess 18 of the other socket 13 and similarly connected to the spider 22 thereof so that the lamp 29 will be resiliently mounted therebetween. It is to be understood that one of the contact posts 20 is adapted to be connected to a positive conductor wire and the other contact post 20 is adapted to be connected to a negative conductor wire, said wires not being shown, to complete a circuit from the positive conductor wire through the contact post 20 to which it is connected, through the spring 21 connected to said contact post, through the spider 22 connected to said spring, through the fingers 27 or the bolt 23 of said spider to the metallic cap 28 at the end of the fluorescent lamp 29 which is mounted in said spider, through the filament of the lamp and then through the corresponding parts of the

other socket 13 to the negative conductor wire to complete the circuit.

It will be obvious that the lamp 29 may be readily removed by moving it inwardly of one or the other sockets 13 to release the opposite end from the other socket 13 after which the first mentioned end may be readily removed.

Various modifications and changes are contemplated and may obviously be resorted to, as only a preferred embodiment of the invention has 10 been disclosed.

I claim as my invention:

A support and electrical connection for mounting an end of a fluorescent lamp, comprising a fixedly disposed socket of insulating material having an open end and a partially closed end, 15 a stationary contact post mounted in the partially closed end of the socket, an expansion coil

spring disposed in the socket and having one of its ends connected to said post and secured thereby to the partially closed end of the socket, a clip, of conducting material, having a flat base and outwardly projecting fingers, said fingers being bent at right angles, intermediate of their ends, the terminal portions of said fingers all projecting in the same direction from the base and being resilient and adapted to yieldably and frictionally engage the metallic end of a fluorescent lamp, a disk disposed on the side of the base opposite to the side thereof from which said terminal portions project, and fastening means connecting said base and disk, and the opposite end of the spring being clamped between the disk and base for detachably connecting the end of the lamp to the socket contact post.
